CLAIM

The ornamental design for a mortarless masonry block, as shown and described.

DESCRIPTION

FIG. 1 is a front perspective view of a mortarless masonry block showing my new design;

FIG. 2 is a top plan view thereof;

FIG. 3 is a bottom plan view thereof;

FIG. 4 is a side elevational view, the opposite side being a mirror image thereof;

FIG. 5 is a right end elevational view thereof; and,

FIG. 6 is a left end elevational view thereof.

FIG. 1

FIG. 2

FIG. 3

FIG. 4

FIG. 5

FIG. 6
